UNITED STATES PATENT OFFICE

WARREN M. SAMPLE, OF MUNCIE, INDIANA

DESIGN FOR A REFRIGERATOR STAND

Application filed May 20, 1930. Serial No. 35,702. Term of patent 14 years.

To all whom it may concern:

Be it known that I, WARREN M. SAMPLE, a citizen of the United States of America, residing at Muncie, in the county of Delaware and State of Indiana, have invented a new, original, and ornamental Design for Refrigerator Stand, of which the following is a specification, reference being had to the accompanying drawing, forming part thereof.

The figure is a view in perspective of a refrigerator stand, showing my new design.

I claim:

The ornamental design for a refrigerator stand, as shown.

WARREN M. SAMPLE.
